UNITED STATES PATENT OFFICE

ROBERT C. LEGAT, OF NEW BRITAIN, CONNECTICUT, ASSIGNOR TO G. E. PRENTICE MANUFACTURING COMPANY, OF NEW BRITAIN, CONNECTICUT, A CORPORATION OF CONNECTICUT

SLIDER FOR FASTENERS

Application filed November 21, 1928. Serial No. 320,885.

- This invention relates to separable fasteners of that kind in which series of complementary interlocking elements are arranged along the opposed edges of a gap or opening 5 in a garment, shoe, receptacle, or other article made of such flexible material as textile fabric, leather, or rubber, and relates more particularly to sliders for such fasteners.
- 10 For certain purposes fasteners of the above type as ordinarily made are not wholly satisfactory, since with the usual construction it is necessary permanently to close the gap or opening in the garment at one end. 15 Thus when employed for closing the fronts of sweaters, coats, and the like, it is necessary for the wearer to draw the garment over his head when putting it on or taking it off, whereas the older forms of fastener, 20 such as hooks, snaps, or buttons, are not open to this objection.
- I am aware that certain attempts have heretofore been made to remedy this deficiency in fasteners of the present type by making the slider in two parts capable of separation so that the gap can be opened intermediate its ends, but so far as is known to me, 25 all such previous expedients have been objectionable either from the standpoint of the cost of production of the fastener, from the cumbersome and unsightly appearance of the device, or from the difficulty of assembling and separating their parts.
- In accordance with the present invention 30 I have followed a similar course in that I divide my slider into two separable sections, but in so doing have avoided complexity of construction, or abnormal size or appearance, and in accordance with a preferred 35 method herein disclosed I provide a slider which may be formed from sheet material by simple stamping and bending operations; which is light in weight; of relatively small dimensions; stiff and durable; which may be 40 made at low cost; whose parts are preferably united by a snap socket connection permitting them readily to be separated or assembled without moving them relatively in a longitudinal direction, and without manipulating latches or equivalent means, and by

such separation permitting the gap to be opened at any desired point; and which works smoothly and freely in opening and closing the gap.

In the accompanying drawings,

Fig. 1 is a front elevation of diagrammatic character illustrating the application of my improved fastener to a sweater coat, showing the actuating slider at the upper limit of its travel and the front of the coat closed;

Fig. 2 is a similar view showing the parts of the slider separated and the front of the coat completely open;

Fig. 3 is a fragmentary front elevation, to large scale, showing the assembled slider removed from the garment;

Fig. 4 is a front elevation of the left-hand guide element of the slider;

Fig. 5 is a front elevation of the right-hand guide element of the slider, together with the back member which is attached thereto;

Fig. 6 is an edge elevation of the part shown in Fig. 4 viewed from the right-hand side of the latter figure;

Fig. 7 is an edge elevation of the right-hand guide element, partly in section, along the line 7—7 of Fig. 5;

Fig. 8 is a transverse section substantially on the line 8—8 of Fig. 3;

Fig. 9 is a plan view, to substantially normal scale, of a blank employed in forming the left-hand guide member of Fig. 4;

Fig. 10 is a plan view of the blank for making the back member of the slider;

Fig. 11 is a plan view of a blank employed in making the right-hand guide element of the slider;

Fig. 12 is a top plan view of the slider, omitting the pull device, illustrating the mode of separating the sections of the slider; and

Fig. 13 is a transverse section of an end stop member of a preferred form.

Referring to the drawings, the numeral 1 designates a coat or sweater provided at the edges of its front opening with series 2 and 3 of fastener elements of any well known type. These fastener elements, for example, may be of the kind disclosed in the patent to Prentice No. 1,658,392, February 17, 1928, wherein the several elements of each

series are independent, or, on the other hand, the fastener elements may be of the type shown in the patent to Prentice No. 1,677,408, dated July 17, 1928, wherein the elements of 5 a series constitute the turns of a helical coil spring, it being understood that whatever specific type of fastener element be employed, the guide elements of the slider hereinafter more fully described will be of appropriate shape to accommodate the fastener elements.

10 Preferably a stop 4 is secured at the upper and lower ends respectively of each of the series 2 and 3 of fastener elements. Such stop is preferably of sheet material and may well 15 be of the kind shown in Figs. 7 and 8 of the patent to Prentice No. 1,658,392 above referred to. However, it is contemplated that other forms of stop may be employed and the specific form of stop forms no essential 20 part of the present invention.

25 In Fig. 1 the front opening in the garment is shown as closed, the series 2 and 3 of fastener elements being interengaged and the actuating slider 5 being disposed at the top of the opening. The extreme bottom of the opening below the ends of the fastener elements is preferably provided with a flap 6 having a buttonhole for engagement with a button 7. Obviously a hook and eye, snap, or 30 any other equivalent means may be substituted for the button and buttonhole. While this auxiliary fastener is not necessary, it is preferable to employ it or its equivalent in order that flexing of the garment at its lower 35 part may not result in separation of the series 2 and 3 of interengaging fastener elements.

40 Referring more particularly to Figs. 3 to 7, the improved slider 5 comprises the left-hand section 11 and the right-hand section 12, it being understood that I refer to these parts as left-hand and right-hand sections merely for convenience in description and that I do not necessarily limit myself to this 45 particular relative arrangement since the parts may be reversed in position, if desired, without departing from the spirit of the invention. The right-hand section includes a back member 8 of resilient and preferably thin sheet material having forwardly turned 50 flanges 9 and 10 (Fig. 8) at its edges. The right-hand section 12, as shown more particularly in Figs. 5, 7 and 8, comprises a fastener guide having a rear wall 13, an inner wall 14 and a front wall 15, the rear and 55 front walls being provided with inwardly directed flanges 16 and 17 (Fig. 8), defining between them a slot leading into the guide channel 18. This guide channel is adapted to receive the right-hand series 3 of fastener 60 elements and the walls of this channel may be shaped appropriately to receive the particular type of fastener element with which the slider is to be employed.

65 In assembling the right-hand guide with the back member, it is disposed against the

front face of the back member with its flange 16 engaging the flange 10. When thus positioned, the inner wall 14 of the right-hand guide cooperates with the resilient back member 8 and its flange 9 to form a resilient snap socket for the reception of the left-hand guide element as hereinafter more fully described. The rear wall 13 of the right-hand guide preferably is furnished with lugs 19 (Fig. 7) which are bent over against the 70 rear side of the back member 8, thus securing the guide permanently to the back member. Obviously, other fastening means may be used if desired.

75 The front wall 15 of the right-hand guide is furnished with a forwardly directed lug M provided with an elongate slot S for the reception of a tongue 29 carried by the left-hand section 11, as hereinafter described. The front member 15 of the right-hand guide 80 is also provided with a tongue member 20 which extends first upwardly, and then downwardly in parallel relation to the front wall 15, and whose lower end is engaged by the bent-up end portion of a second tongue 21 85 extending downwardly from the wall 15. The tongues 20 and 21 form a loop adapted to receive a pull device 22 having an opening through which the loop passes, the pull device being movable from the lower part 90 of the loop to the upper part to facilitate movement of the slider in either direction.

95 The left-hand section 11 comprises a guide having a rear wall 23 (Fig. 8), a front wall 24, and an inner wall 25, the outer edges of the walls 23 and 24 being bent to form inwardly directed flanges 26 and 27 respectively defining between them a slot leading into the guide channel 28 for the left-hand series 100 of fastener elements 2. The inner walls 14 and 25 of the right-hand and left-hand guides extend only part way down the length of the slider so that the guide channels 18 and 28 merge at the lower end of the slider as is usual in sliders of this type. If desired, the 105 lower edges of the walls 14 and 25 may be beveled so as collectively to form a wedge-shaped divider plate to facilitate separation 110 of the slider elements of the opposed series.

115 The front wall 24 of the left-hand guide is furnished with the forwardly divergent tongue 29 adapted to pass through the slot S above described and to prevent relative longitudinal movement of the sections, thus assisting in holding the left-hand section 11 120 in proper assembled relation with the right-hand section.

125 The back member 8 extends across the entire width of the slider, being of such dimensions that when the left-hand section 11 is pressed into the forwardly open snap socket (defined by the outer surface of wall 14, the front face of the back member 8, and the right-hand face of resilient flange 9,) the flange 9 frictionally engages the flange 26 of 130

section 11, tending to prevent the latter from springing forward and away from the back. Before snapping the section 11 into its socket, the tongue 29 is first inserted in the slot S, and the engagement of these parts effectively prevents relative longitudinal movement of the slider sections during use. When it is desired to separate the parts of the fastener, it is simply necessary to grasp the garment 10 closely adjacent to the slider at opposite sides and by pulling sharply forward on that side of the garment which engages the section 11, as indicated in Fig. 12, the section 11 may be sprung away from the back member, swinging about its line of contact with the right-hand guide as an axis, whereupon the slider sections separate, and the engaged series of fastener elements drop freely apart, leaving the gap open, as shown in Fig. 2.

20 In constructing the slider above described, I preferably prepare blanks, such as shown in Figs. 9, 10 and 11, by suitably stamping or punching them from sheet material by means of dies or otherwise. Thus, as shown 25 in Fig. 9, the blank 11^a is suitably shaped for making the left-hand section 11 of the slider. This blank, as shown, comprises parts 26^a, 27^a and 29^a which when bent along the dotted lines are adapted to form the side 30 flanges and the tongue of the guide member 11.

In Fig. 10 I have shown the blank 8^a which is adapted to form the back of the completed slider.

35 In Fig. 11 I have indicated a blank 12^a appropriate for forming the right-hand guide member of section 12. This blank comprises parts 13^a, 14^a, 15^a, 16^a, 17^a, 19^a, 20^a and 21^a which when bent along the dotted lines 40 and at certain other obvious points are adapted respectively to constitute the parts 13, 14, 15, 16, 17, 19 and 20 of the guide. This blank has the punched out slot S, and the incision B defining the lug M. Having provided the 45 blank 12^a, its various parts, with the exception of the tabs 19^a, are bent to proper position, the pull device 22 being threaded over the tongue 20^a before the latter is engaged with the tongue 21^a. The back member 8^a is 50 then arranged against the outer wall of the member 13^a and the tabs 19^a are turned over to hold the back member in place.

The completed sections 11 and 12 are now 55 mounted on the left-hand and right-hand series respectively of fastener elements and the stops 4 are secured in position. The sections 11 and 12 are moved down to the lower end of the series of fastener elements; the section 11 is engaged with the socket in the section 12; and the slide is ready for use. The operation of the slide has already been described.

While I have herein disclosed one desirable embodiment of the invention and have described a desirable mode of making this em-

bodiment, I wish it to be understood that the invention is not limited to the specific details of construction herein disclosed or to the specific mode of making the device, but that variations in shape, size and relative arrangement of parts, and the substitution of equivalents may be made, and that a different order of steps in making the device may be adopted without departing from the spirit of the invention.

I claim:

1. A slider for separable fasteners of the class described, said slider comprising two independent sections each having a guide channel for one series of fasteners, one of said sections having elements constituting a snap socket for the reception of the other section.

2. A slider of the class described comprising two independent sections each provided with a guide channel for one series of fastener elements, one of said sections having spaced elements extending substantially from top to bottom of the slider and between which the other section fits.

3. A slider of the class described comprising two independent sections each provided with a guide channel for one series of fastener elements, one of said sections being of substantially the full width of the slider and having a socket for the reception of the other section.

4. A slider for separable fasteners of the class described comprising a pair of independent separable sections, each section having a portion containing a channel for one series of fastener elements, one of said sections having a forwardly open socket into which the channel containing portion of the other section fits.

5. A slider for separable fasteners of the class described comprising a pair of independent separable sections, each section defining a channel for one series of fastener elements, one of said sections having a forwardly open socket for the reception of the other section, said socket having at least one resilient wall adapted frictionally to engage the other section when seated in the socket.

6. A slider for separable fasteners of the class described comprising a pair of independent separable sections, each section having a portion containing a channel for one series of fastener elements, one of said sections having longitudinally extending spaced members defining an elongate socket for the reception of the channel containing portion of the other section, said socket being so arranged as to permit engagement and separation of the sections without relative movement thereof in a longitudinal direction.

7. A slider for separable fasteners of the class described comprising a pair of independent separable sections, each section having a portion containing a channel for one series of fastener members, one of said sec-

5 tions comprising elements constituting a snap socket in which the channel containing portion of the other section fits, said elements being arranged to resist force tending to separate the sections in a lateral direction but permitting one of said sections to swing forwardly relatively to the other to allow separation.

8. A slider for separable fasteners of the class described comprising a pair of independent separable sections, each section having an elongate portion containing a channel for one series of fastener elements, one of said sections having a longitudinally extending socket for the reception of the channel containing portion of the other section, and means preventing relative longitudinal movement of the assembled sections.

9. A slider for separable fasteners of the class described comprising a pair of independent separable sections, each section having a portion containing a channel for one series of fastener elements, one of said sections having a flange spaced from its channel containing portion to form a socket between them for the reception of the channel containing portion of the other section, the socket forming parts being so constructed and arranged as to permit the sections to be assembled or separated by movement of one relatively to the other substantially perpendicular to the longitudinal axis of the slider.

10. A slider for separable fasteners of the class described comprising a pair of independent separable sections, each section having a portion containing a channel for one series of fastener elements, one of said sections having a vertically elongate socket for the reception of the channel containing portion of the other section, and a tongue carried by one section engaging an opening in the other to prevent longitudinal movement of the assembled sections relatively to one another.

11. A slider for separable fasteners of the class described comprising a pair of independent separable sections, each section defining a channel for one series of fastener elements, one of said sections comprising a pull retaining element extending from the upper to the lower part of the slider, a part having a slot therein, and a laterally extending back member provided with a retaining flange, said back member being separably connected to said section, the other section having a tongue engageable with the aforesaid slot in the first section, said other section normally engaging the retaining flange of the back member.

12. A slider for separable fasteners of the class described comprising a pair of independent separable sections, each section having a guide defining a channel for one series of fastener elements, a back member, tabs uniting one of the guides to the back member,

said guide having a forwardly directed lug provided with a slot, and a tongue projecting laterally from the other guide, the last named guide being separably connected to said back member and said tongue being adapted to enter said slot when the parts are assembled thereby preventing relative longitudinal movement of the sections.

13. A four-part slider for separable fasteners of the class described comprising a 75 back member, a pair of independent separable sections, each including a portion defining a guide channel for one series of fasteners, one of said sections being permanently attached to the back member, and a pull attached to said latter section, the other of said sections being separably connected to said back member.

14. A slider for separable fasteners of the class described comprising a pair of independent separable sections, each section having a guide defining a channel for one series of fastener elements, one guide having an integral pull retaining tongue projecting upwardly and then forwardly and downwardly, 90 and a second tongue projecting from the lower part of said guide and engaging the lower end of the first tongue.

15. A slider for separable fasteners of the class described comprising a pair of independent separable sections, each section having a guide defining a channel for one series of fastener elements, one of said sections having a back member extending laterally from its fastener guide, said back member having a lateral flange cooperating with its associated guide to provide an elongate socket for the reception of the channel defining guide of the other section.

16. A slider for separable fasteners of the class described comprising a pair of independent separable sections, each section having a guide defining a channel for one series of fastener elements, a back member having forwardly directed lateral flanges, the flanges being spaced to permit the guides of the two sections to be assembled in close fitting relation between said flanges, and means permanently securing one of said guides to the back member.

17. A slider for separable fasteners of the class described comprising a pair of independent separable sections, each section having a guide defining a channel for one series of fastener elements, one of said sections having a back member secured to its fastener guide and projecting laterally from said guide, the back member having a forwardly directed flange cooperating with the opposed wall of said guide to form a socket for the reception of the other section.

18. A slider for separable fasteners of the class described comprising a pair of independent separable sections, each section having a guide defining a channel for one series 130

of fastener elements, the guide of each section including front, rear, and inner walls, the inner walls of the two guides being normally in engagement, one of said sections comprising a back member engaging the rear walls of both guides and having lateral flanges confining the assembled guides between them.

Signed by me at Berlin, Connecticut, this nineteenth day of November, 1928.
